UNITED STATES PATENT OFFICE.

EDGAR DAY KNAP, OF SCHENECTADY, AND SEVERN D. SPRONG, OF EAST GREENBUSH, NEW YORK.

MAGNETIC PERMEAMETER.

SPECIFICATION forming part of Letters Patent No. 508,827, dated November 14, 1893.

Application filed June 28, 1893. Serial No. 479,072. (No model.)

To all whom it may concern.

Be it known that we, EDGAR DAY KNAP, of Schenectady, in the county of Schenectady, and SEVERN D. SPRONG, of East Greenbush, 5 in the county of Rensselaer, State of New York, have invented a new and Improved Magnetic Permeameter, of which the following is a specification, reference being had to the annexed drawings, forming a part there-
of, in which—

Figure 1 is a front elevation of our improved magnetic permeameter. Fig. 2 is a vertical transverse section, taken on line 2—2 in Fig. 1. Fig. 3 is an inverted plan view, with the bottom 15 of the casing removed. Fig. 4 is a horizontal section taken on line 4—4 in Fig. 1. Fig. 5 is a vertical transverse section taken on line 5—5 in Fig. 3.

Similar figures and letters of reference indicate corresponding parts in all the views.

The object of our invention is to construct an instrument by means of which the magnetic permeability of a body of iron may be readily determined, the instrument being especially designed for testing iron used in the construction of dynamos and motors, more particularly in the field magnets of such machines.

Our invention consists in the combination 30 with the field magnet having oblique pole pieces, of a soft iron armature arranged to turn between the pole pieces and having oblique wings or arms, the oblique pole pieces being arranged diagonally opposite each other, 35 the wings of the armature being also arranged diagonally opposite each other to avoid a magnetic short circuit in the instrument. It also consists in polar extensions formed on or attached to the poles of the field magnet, for 40 forming contact with the iron to be tested, all as will be hereinafter more fully described.

In carrying out our invention, we employ a magnetic shunt in which one branch is an armature in the field of a magnet, the other 45 branch being through polar extensions of the magnet and the iron to be measured. The instrument is designed to work by the balance of the shunt, including the iron to be measured, the pull of the magnet on the armature being opposed by a spring in such a manner that when the field of the instrument

is weakened by the flux of magnetic force through the iron (to be measured) composing the shunt, the armature will change its position, the movement of the armature being indicated by a suitable index. This movement will be proportional to the flux through the shunt, and the flux through the shunt will be proportional to the quality of the iron forming the shunt. 55

The field magnet 10 is provided with pole pieces 11 attached to or formed upon the polar extremities of the magnet, and a portion of each pole piece projects inwardly and is cut off obliquely, the inwardly-extending oblique 60 portions being arranged diagonally opposite each other. In the center of the space between the pole pieces 11, is journaled an arbor 15, on which is mounted a sleeve 14, to the ends of which are attached the wings 13 65 of the armature. The said wings are made of soft iron, as is also the sleeve 14—each of the wings to be in the form of a segment of a hollow truncated cone, each segment comprising about ninety degrees. The said wings 13 70 are arranged diagonally opposite each other, and are fitted to revolve near but not in contact with the pole pieces 11. The concave faces of the pole pieces opposite the wings of the armature are of conical form, and of about 75 the same shape and extent as the outer faces of the armature wings. 80

On the arbor 15 is mounted an index 17, which moves in front of a scale 18 attached to the top of the magnet 10, and to the said 85 arbor is secured the inner end of a volute spring 19, the outer end of which is attached to the inner end of a lever 20, the said end of the said spring being inserted in a slit *e* in the arm *d*, of the said lever. The lever 20 is 90 journaled on a boss on the inner face of one of the bars 16, which is attached to the pole piece 11 of the magnet and supports one of the bearings of the arbor 15. The outer end of the lever 20 projects beyond the bar 16, 95 where it may be readily grasped when it is desired to adjust the instrument.

The magnet 10 is provided with polar extensions 12, which are for the purpose of forming a magnetic contact with the body of iron 100 to be tested. The pull of the magnet on the armature is opposed by the spring 19, and

the said spring is adjusted so as to hold the index 17 and the armature normally in the zero position. When the polar extremities 12 are placed upon or in magnetic contact 5 with a body A of iron, the magnetic permeability of which it is desired to measure, the said body of iron forms a shunt to the magnet 10, so that its attractive power is weakened, thereby releasing the armature in pro- 10 portion to the diminution of the magnetic strength, allowing the volute spring 19 to carry the wings 13 more or less out of the field of force. When this amount is indicated by the index 17 on the scale 18, it shows 15 the degree of magnetic permeability of the body of iron being tested. By the diagonal arrangement of the pole pieces and of the armature wings, the greatest possible deflection is secured without creating a magnetic short 20 circuit by anything short of a deflection of one hundred and eighty degrees.

To insure the greatest possible accuracy, the pivots b of the arbor 15 are journaled in jeweled bearings a a', supported in the bars 25 16; and to protect the instrument from injury and dust, it is inclosed in a casing 21, having the front end closed by a glass window 22.

Having thus described our invention, we 30 claim as new and desire to secure by Letters Patent—

1. A magnetic permeameter, formed of a field magnet having polar extensions for contact with the metal to be tested, an armature 35 pivotally supported within the field of the magnet, and a spring for opposing the pull of the magnet on the armature, substantially as specified.

2. A magnetic permeameter, consisting of a 40 field magnet, an armature pivotally supported within the field of the magnet, the magnet and armature with the metal to be tested forming a shunt magnetic circuit in which the metal to be tested is in one branch, the 45 armature being in the other branch, substantially as specified.

3. In a magnetic permeameter, a magnet having polar extensions of reduced diameter for localizing the magnetic action of the instrument, substantially as herein specified. 50

4. A magnetic permeameter, wherein a movable armature forms one branch of a mag-

netic shunt, and in which the metal to be tested forms the other branch of the magnetic shunt, as herein specified.

5. A magnetic permeameter, formed of a field magnet having oblique pole pieces, an armature having two wings formed of segments of the frustum of a truncated hollow cone and oppositely arranged with respect to 60 each other, and a spring attached to the armature and arranged to oppose the pull of the magnet on the armature, substantially as specified.

6. A magnetic permeameter, formed of a field magnet having oblique pole pieces, an armature having two wings formed of segments of the frustum of a truncated hollow cone and oppositely arranged with respect to 70 each other, a spring attached to the armature, an index carried by the armature arbor, and a fixed scale arranged for use in connection with the index, substantially as specified.

7. In a permeameter, the combination of a field magnet provided with polar extensions 75 for contacting with the iron to be measured, a soft iron armature placed between poles of the magnet, a spring for opposing the turning of the armature, and means for indicating the motion of the armature, substantially 80 as specified.

8. The combination with a field magnet provided with pole pieces and polar extensions projecting from the pole pieces, of a pivoted armature between the pole pieces, having convex faces that are diagonal to the axis 85 of the armature and conform to concave faces of the pole-pieces, an indicating hand, an opposing spring, and a graduated scale, substantially as specified.

9. The combination, with a field magnet provided with pole-pieces and polar extensions projecting from the pole pieces, of a pivoted armature between the pole pieces, having convex faces that are diagonal to the axis 95 of the armature and conform to concave faces on the pole-pieces, an indicating hand, an opposing spring, a regulator for the spring, and a graduated scale, substantially as specified.
